ROTATABLE DISPLAY FIXTURE

Sherburne D. Levings, Winnetka, Ill.

Application June 16, 1953, Serial No. 25,520

Term of patent 14 years

(Cl. D1—12)

Fig. 1 is a front elevational view of a rotatable display fixture showing my new design;

Fig. 2 is a side elevational view thereof;

Fig. 3 is a top view thereof.

The dominant feature of my design resides in the rotatable display fixture shown in full lines.

I claim:

The ornamental design for a rotatable display fixture, as shown and described.
